UNITED STATES PATENT OFFICE.

JOHN MERRY, OF NEW YORK, N. Y., ASSIGNOR TO BIGELOW CARPET COMPANY, A CORPORATION OF MASSACHUSETTS.

DESIGN FOR A RUG.

41,312.

Specification for Design.

Patented Apr. 11, 1911.

Application filed February 9, 1911. Serial No. 607,698. Term of patent 7 years.

To all whom it may concern:

Be it known that I, JOHN MERRY, a subject of the King of Great Britain, residing at New York city, in the county of New York and State of New York, have invented a new, original, and ornamental Design for a Rug, of which the following is a specification, reference being had to the accompanying drawing, forming part thereof.

The drawing illustrates one quarter of a rug showing my new design, the remaining three quarters being duplicates thereof.

I claim:

The ornamental design for a rug, as shown.
JOHN MERRY.
